US0D1111921S

(12) **United States Design Patent** (10) Patent No.: **US D1,111,921 S**
(45) Date of Patent: ** Feb. 10, 2026

(54) **PAIR OF HEADLIGHTS FOR A VEHICLE**

(71) Applicants: **Rivian IP Holdings, LLC**, Plymouth, MI (US); **Amazon Technologies, Inc.**, Seattle, WA (US)

(72) Inventors: **Nicholas Adam Malachowski**, Bloomfield Hills, MI (US); **Stephen Mark Goodrich**, Southfield, MI (US); **Luke James Mack**, Newport Beach, CA (US); **Mohamad Jeffery Hammoud**, Bloomfield Hills, MI (US); **John Sokol**, Sammamish, WA (US); **Ross Rachey**, Bellevue, WA (US); **Benjamin Hewitt**, Seattle, WA (US); **Christopher Gordon**, Bellevue, WA (US)

(73) Assignees: **Rivian IP Holdings, LLC**, Plymouth, MI (US); **Amazon Technologies, Inc.**, Seattle, WA (US)

(**) Term: **15 Years**

(21) Appl. No.: **29/889,092**

(22) Filed: **Apr. 7, 2023**

Related U.S. Application Data

(63) Continuation of application No. 29/853,626, filed on Sep. 16, 2022, now Pat. No. Des. 1,008,132, which is a continuation of application No. 29/769,555, filed on Feb. 5, 2021, now Pat. No. Des. 964,899.

(57) **CLAIM**

The ornamental design for pair of headlights for a vehicle as shown and described.

DESCRIPTION

FIG. 1 is a front-right corner perspective view of pair of headlights for a vehicle showing the claimed design;

FIG. 2 is a front view of the vehicle headlights;

FIG. 3 is a front-left corner perspective view of the vehicle headlights showing the claimed design;

FIG. 4 is a left-side view of the vehicle headlights;

FIG. 5 is a right-side view of the vehicle headlights; and,

FIG. 6 is a top view of the vehicle headlights.

Features of the Vehicle rendered in broken lines surrounding the vehicle headlights form no part of the claimed design, and the dashed-dot line shows a boundary of the unclaimed portion of the Vehicle and forms no part of the claimed design.

1 Claim, 5 Drawing Sheets
